(57) **CLAIM**

The ornamental design for an ornate flower for kitchen utility articles, as shown and described.

DESCRIPTION

FIG. 1 is a perspective view of an ornate flower for kitchen utility articles incorporated in a napkin or coaster holder, showing our new design;

FIG. 2 is a front elevational view thereof, the rear elevational view being a mirror image;

FIG. 3 is a side elevational view thereof; and,

FIGS. 4–6 are perspective views of the ornate flower of the invention incorporated in other kitchen utility articles wherein the dotted lines form no part of the claimed design.

The dotted line disclosure of elements in the views is for illustrative purposes only and forms no part of the claimed design.
